COMBINED BILL FOLD AND COIN HOLDER

Myron L. Wilner, 353 Leonard St., Brooklyn, N.Y.

Filed July 8, 1964, Ser. No. 80,766

Term of patent 14 years

(Cl. D87—3)

FIG. 1

FIG. 3

FIG. 4

FIG. 2

FIG. 1 is a front perspective view of a combined bill fold and coin holder showing my new design;

FIG. 2 is a left-side elevational view thereof;

FIG. 3 is a rear elevational view thereof;

FIG. 4 is a bottom plan view thereof.

I claim:

The ornamental design for a combined bill fold and coin holder, substantially as shown.
